UNITED STATES PATENT OFFICE.

EDWARD L. MEGILL, OF NEW YORK, N. Y.

FEED-GAGE FOR USE ON PRINTING-PRESSES.

1,370,827.

Specification of Letters Patent.

Patented Mar. 8, 1921.

Application filed June 24, 1919. Serial No. 306,336.

To all whom it may concern:

Be it known that I, EDWARD L. MEGILL, a citizen of the United States, residing at New York, in the county of New York and State of New York, have invented certain new and useful Improvements in Feed-Gages for Use on Printing-Presses, of which the following is a specification.

This invention relates to improvements in what are commonly called feed gages for use on printing presses, and which are secured to the tympan sheets on the platen of the press to serve as stops or rests, locating the position of the sheets to be printed, so that they may be properly presented to the type. I have in mind particularly the sort of gages in which there is one part that is inserted through a hole or slit in the tympan sheet, and lies below this sheet, and another part connected to the first part, which over-lies the tympan sheet, the sheet being gripped between these two parts.

A gage of this general type may include a vertical gage head, which normally stands perpendicular and when fast to the tympan is at right angles with the surface thereof; also a prong member which passes under the tympan, said prong member being integral with and extending rearwardly from the lower edge of the gage head, integral presser arms extending rearwardly from the upper edge of the gage head and resting upon the upper surface of the tympan and coöoperating therewith to support the gage head. In devices of this character there has also been employed a sliding tongue projecting through an aperture in the vertical gage head, the lower end of this sliding tongue being widened and bent around the outer edges of the presser arms. Usually also the lower edge of the gage head, and each side of the prong which projects therefrom, is provided with downwardly projecting teeth, which are to be forced into the tympan sheet to hold the gage in desired position.

It is one of the objects of the present invention to construct a gage pin in such a way that the gage head will have an unbroken lower edge, except for such holding teeth as may be formed thereon; that is to say, I aim to provide a construction in which the holding prong does not spring from the lower edge of the gage head proper, so that the whole lower edge may be provided with

teeth as desired. Furthermore, I aim to provide a construction in which the root end of the holding prong is not in the line of the teeth but is integral with the lower edge of an arch member parallel to the gage head proper and constituting, with the gage head proper said arch, so that there is a space between the teeth and the inner end of the holding prong and consequently less liability of the teeth being gouged into the tympan paper when the prong is inserted into the tympan to the full extent. The possible additional teeth on the lower edge of the gage head, in connection with the customary teeth at the corners of the gage head adds considerable strength to the bite on the tympan. The teeth are sure to gouge into the tympan if they are close to the end of the prong and if the prong is pushed all the way into the tympan. Therefore, I form an arch between the prong and the teeth and prevent the teeth from puncturing or dragging through the tympan when the prong is pushed in full length. In other words, the gage head instead of being a vertical member with arms extending backward from its upper edge and a prong extending backward from its lower edge is made in the form of a U, one member of which is the gage head proper with teeth on its lower edge, and the other member of which is parallel to the gage head proper and has the prong and the presser arms extending rearwardly from its lower edge portion, these two parallel parts of the U member being spaced apart by a cross-piece or co-acting member. And I provide that in the space between the two parts of the U member there shall be mounted a substitute for the sliding tongue in such fashion that it may be readily depressed when it is brought in contact with the furniture in the chase and will spring back when this contact ceases without possibility of disarrangement. This substitute for the usual spring tongue may however be readily detached for purposes of replacement or repair and the necessity for punching a hole through the gage head proper is eliminated.

Furthermore, by reason of the new relation between the holding prong and the gage head and the resulting possibility of having teeth in the middle of the lower edge of the gage head as well as toward the ends thereof, I am enabled not only to obtain a

stronger bite on the upper sheets of the tympan, and to reduce the depth of the penetration which would be required where fewer teeth were used, which would necessarily have to be longer and which cause destruction of the under sheets or card packing of the tympan; but also due to this relation of the teeth and prong, the teeth may be released from the tympan and the 10 gage pin moved for betterment of the register without fracturing the tympan paper around the tooth holes.

Another advantage resulting from the new relation which I have devised between the 15 prong and the gage head proper, is that I am able to produce from a blank of a given length, a variety of heights of gage head as is required in the printing of different stock. This is done by having the portion of the 20 blank of which the gage head is formed made of a given width, perfectly flat and free from side extensions, or notches or insets, with parallel side edges; and by simply bending the blank crosswise at the desired 25 places, a variety of heights for the gage head may be readily and cheaply made. The angles of bend are made on lines to produce the desired height of the front and rear plates, which are the parts of the U 30 member herein referred to, and which determine the height of the gage on the tympan. A further object is to confine all rigid high parts of the device within a narrow compass, so that when the sheet gripper 35 of the press is connected to grip the end of the sheet, the gage head may pass through a narrow opening provided in the sheet gripper, to permit the gripper to come down on the margin of the stock which is being printed, the substitute for the sliding tongue as 40 before stated, being readily compressible by that part of the gripper with which it comes in contact.

Other objects and aims of the invention, 45 more or less broad than those stated above, together with the advantages inherent, will be in part obvious and in part specifically referred to in the course of the following description of the elements, combinations, arrangements of parts, and applications of 50 principles constituting the invention; and the scope of protection contemplated will appear from the claims.

In the accompanying drawings, which are 55 to be taken as part of this specification, and in which I have shown merely a preferred form of embodiment of invention, Figure 1 is a plan view showing my invention as applied to a tympan and showing also its relation to a sheet which is being printed and to a gripper finger; Fig. 2 is a plan view of a blank from which a gage pin such as shown in Fig. 4 may be formed up; Fig. 3 shows a blank of the same over-all length, but 60 65 which when formed up will produce a gage

pin of the height shown in Fig. 5; Fig. 4 is a sectional view as taken on the line 4-4 of Fig. 2, when the subject-matter of Fig. 2 has been formed up by bending it along the dotted lines appearing in Fig. 2; Fig. 5 is 70 a view similar to Fig. 4 of a gage pin made by forming up the blank shown in Fig. 3; Fig. 6 is a perspective view of a gage pin made in accordance with my invention, showing a compressible tongue mounted on 75 the arch portion of the gage head; Fig. 7 is a detail view of the spring tongue detached; Fig. 8 is a plan view of one of the gage pins carrying a transversely extending spring tongue which adapts it for use particularly as a side gage, with machine feeding; and Fig. 9 is a detail of the spring tongue shown in Fig. 8.

Referring to the numerals on the drawings, 8 indicates a tympan and 9 a sheet of 85 stock which is to be printed. 10 indicates a gripper finger, which is provided with a long narrow slot or opening 11. The gage pin comprises a blank such as shown in Figs. 2 and 3 generally oblong and having a forward portion 12 with teeth 14 on its edge. This forward portion 12 of the gage pin blank is bent along the dotted lines 15, 16 and 17, to form a U-shaped part as shown in Figs. 4, 5 and 6, the outer part of the U-shaped member, indicated at 18, being provided with the teeth 14 at its lower edge, and the inner part 19 of the U-shaped member being parallel to the forward member or gage head proper 18, and the two parts 100 18 and 19 being connected by the cross-piece or connecting member 20, which is preferably flat. Appreciably back of the bending line 17 of the blank, as shown in Figs. 2 and 3, the blank is cut out to form parallel 105 presser arms 22, which are to rest on top of the tympan, and between these two presser arms 22 a holding prong 24 with a pointed end 25, this holding prong being intended to be inserted beneath the tympan sheet, 110 so that the tympan sheet is between the arms 22 and the prong 24. It will be observed that the side edges of the blank are parallel and there are no extensions or notches or insets, except those which are necessary to 115 produce the teeth 14, the arms 22 and the prong 24. The lower edge of the gage head proper 18 may be provided with as many teeth as desired, and by increasing the number of teeth the length of them may be 120 reduced, with obvious advantage. Furthermore, the holding prong and the presser arms are flat and substantially rest above the plane of the tympan sheet, so that the end part of the device which projects above 125 the tympan sheet in use to any great extent is the arched gage head portion comprising the two portions 18 and 19 and the connecting member 20. Consequently the gripper finger 10 provided with the cut out 11 may 130

come down flat on the device. And the connecting member 20 is made to serve as a support for a spring tongue, comprising a flat finger 26, integral with and extending upwardly at an angle from a flat arm 27 which passes beneath the arch member 20 and is held in position thereon by a bent portion 28 which overlies the arch member 20. At the junction between the arm 27 and the bent portion 28 the material is given a curvature 29, so that the top member 28 tends to move toward the arm 27. The result of this is that when the spring tongue is in the position as shown in Fig. 6 it tends to keep that position, even though the finger 26 is depressed by the gripper finger as indicated in Fig. 1. The arch gage head thus accommodates the holding portion of the spring tongue, housing it and guiding it in its movement up and down. The holding portion may be readily opened to release or attach it laterally to the housing; and when slipped into place, the flap is held on by the free end 26 which crosses the side edge of the member 18.

As indicated by Figs. 2 and 3, gage pins having gage heads of different heights may be made from blanks of substantially the same over-all length, by properly locating the bending lines 15, 16 and 17 and making the cut outs for the presser arms 22 and prong 24 to the rear of the bending line 17. Thus with a higher gage head the prong will be slightly shorter than with a lower gage head. Otherwise there will be no structural difficulties.

Assuming that the direction of feed of the sheet is according to the arrow at the top of Fig. 1 and that the feeding is done automatically by machine, it is obvious that a side gage such as shown at the lower part of Fig. 1 should have its spring tongue 30 extending transversely of the gage pin, that is to say, in the same general direction as the tongue 26 of the end gage which is also shown in Fig. 1. This result is accomplished by forming the spring tongue as most clearly indicated in Fig. 9, so that when it is slipped into position on the arched housing of the gage the end 31, which is at the left in Fig. 1, is elevated so as to guide the sheet to its desired position flat on the platen.

Inasmuch as many changes could be made in the above construction, and many apparently widely different embodiments of my invention could be made without departing from the scope thereof, it is intended that all matter contained in the above description or shown in the accompanying drawings shall be interpreted as illustrative and not in a limiting sense.

It is also to be understood that the language used in the following claims is intended to cover all the generic and specific features of the invention herein described and all statements of the scope of the inven-

tion which, as a matter of language, might be said to fall therebetween.

I claim:

1. A gage pin having a U-shaped forward portion, the outer arm of the U provided with teeth along its lower edge, the inner arm of the U having a rearward extension at its lower edge with presser arms and a holding prong integral with said extension, and a spring tongue carried by the connecting member of the U-shaped part.

2. A device as set forth in claim 1, in which the spring tongue comprises a clip engaging on both sides of the connecting member of the U-shaped part and having a portion projecting forwardly of the outer member of the U-shaped part.

3. A gage pin having a U-shaped forward portion, the outer arm of the U provided with teeth along its lower edge, the inner arm of the U having a rearward extension at its lower edge with presser arms and a holding prong integral with said extension.

4. A device as set forth in claim 1 in which the spring tongue comprises a clip engaging on both sides of the connecting member of the U-shaped part and having a portion projecting transversely of the presser arms and holding prong.

5. A gage pin having a body portion and a head portion, and a member having an attaching portion engaging the head and a tongue portion in front of the head.

6. A spring tongue for the purpose described having clamping portions to engage on opposite sides of a supporting member, a downwardly bent portion extending from one of the clamping members, a connecting member integral with the said downwardly bent portion and an upwardly extending tongue portion integral with said connecting portion.

7. A gage pin having a body portion and a head portion, and a member having an attaching portion engaging the head and a tongue portion in front of the head and disposed transversely of the body.

8. A gage pin comprising a vertical forward wall, a second wall connected to the upper edge of the first wall and extending downwardly with respect to its line of connection with the first wall, and rearwardly extending members projecting from the lower edge of the second wall and adapted to clamp a tympan sheet.

9. A gage pin having a head comprising a vertical forward wall, a second wall connected to the upper edge of the first wall, and extending downwardly with respect to its line of connection with the first wall, and a tongue member having an attaching portion secured to the head and extending between the two walls thereof.

In testimony whereof I affix my signature.
EDWARD L. MEGILL.
